UNITED STATES PATENT OFFICE.

EMILE FERDINAND DEL BONDIO, OF NEW ORLEANS, LOUISIANA.

BUTTER-WORKER.

SPECIFICATION forming part of Letters Patent No. 276,006, dated April 17, 1883.

Application filed October 27, 1882. (No model.)

To all whom it may concern:

Be it known that I, EMILE FERDINAND DEL BONDIO, a resident of the city of New Orleans, parish of Orleans, and State of Louisiana, have invented a certain new and useful Improvement in Butter-Workers or Machines for Making Butter, &c.; and I do hereby declare the following to be a full, clear, and correct description of the same, reference being had to the annexed drawings, making a part of this specification.

This invention relates to that class of machines used in the manufacture of butter and artificial butter, commonly called "butter," "butterine," "oleomargarine," &c.; and it consists in a novel combination and arrangement of parts by which is secured a thorough utilization of all the butter-making properties contained in milk or in the oil of tallow or other article from which butter, butterine, oleomargarine, &c., is made.

The construction and operation of the machine will be readily understood by referring to the accompanying drawings, whereon—

Figure 1 represents a side elevation of the machine with certain parts thereof in sectional lines. Fig. 2 is a vertical cross-section through the line $x-x$, of Fig. 1. Fig. 3 is a plan or top view of the machine, and Fig. 4 a diagram of some of the working parts thereof.

The frame of this machine is rectangular in form and composed of four vertical pieces, A, fixed at their upper ends by longitudinal pieces B B' and cross-ties C C', and near their lower ends by longitudinal beams D D' and cross-beams E E. On the latter are secured two longitudinal ways or slides, f, having recesses through their whole lengths, in which operates a movable table or trough, G, the latter provided on its under side with a longitudinal rack, h, which is engaged by a pinion, i, that is secured on a shaft, k, which has bearings in the longitudinal pieces D D'. The shaft k is furthermore provided with a ratchet-wheel, l, and with arms m m' on each side thereof, as shown in Fig. 2. In the outer ends of these are slots n for the reception of a pin, o, which is fitted in the lower end of a pendulum, p, that is suspended from a pin, q, which projects inwardly from the piece B, as shown. The pendulum aforesaid is provided at its up-

per end with an inwardly-projecting arm, r, for purposes hereinafter described. Between the arms m m' is pinned a pawl, t, for engaging and operating the ratchet-wheel l and other parts of the machine connected therewith.

The letters H H' designate beams, the ends of which are connected at certain distances apart to the cross-ties C C'. These beams are provided with journal-bearings I I' for the reception of shafts K K', the latter somewhat longer than the former and having additional bearings in the outer longitudinal pieces, B B', and the two shafts connected by gear-wheels, as shown at L L'. The shaft K' is provided with a pulley, M, through which the operating-power is applied. The gear-wheels L' L' are each provided with crank-pins u u', on which are fitted levers or connecting-rods N N', that are pinned to a second set of levers, O O', as shown at v, and to a third set of levers, P P', as at w. The upper ends of the second set of levers, O O', are journaled to the outer ends of a fixed shaft, R, while the lower ends of the same are connected by a shaft, S, on which is hinged or pivoted a beater, T, having angle-levers y y', the outer ends of which are pivoted or bolted to the lower ends of the third set of levers, P P', as shown at a a'.

Near the lower ends of the levers O, and fitted in the upper edge thereof, is a set-screw, b, which, in the upward movement of the said levers, impinges against the under side of the arm r, thereby causing the pendulum to operate and through it the ratchet-wheel l and the means connected therewith for giving an endwise movement to the table or trough G.

In Fig. 4 the operating-levers are shown at their greatest height, as when operating the pendulum.

In the operation of the machine the pawl t is raised, so as to permit of the forward movement of the table or trough G to receive the material to be operated upon. Power is then applied to the pulley M, whereby the whole machine is put in motion.

An important feature in this invention consists in the manner in which the beater is connected with its operating mechanism, which not only serves to alternately raise and lower the same, but also gives to it a "rocking" or

"kneading" motion, which, as the table or trough is moved toward it, insures a thorough working of the material contained therein.

I am aware that machines for working butter have been constructed with beaters having an up-and-down motion combined with a horizontal one. Hence I do not claim the same as my invention; but,

Having described my invention, what I do claim as new, and desire to secure by Letters Patent, is—

1. In combination with the fixed shaft R and the shaft K, carrying wheels L', having pins *u u'*, the levers N and O, the lower ends of the latter having hinged or pivoted thereto a beater, T, substantially as described, and for the purpose specified.

2. The fixed shaft R and the levers O, having a beater, T, hinged or pivoted to the lower ends thereof, with means whereby the said beater is alternately raised and lowered and at the same time imparting thereto a rocking or kneading motion, substantially as and for the purpose set forth.

25 3. In combination with the fixed shaft R and the shaft K, carrying wheels L', having crank-pins *u u'*, the levers N, O, and P, and the beater T, having angle-braces *y*, said levers and braces connected, as described, by pivots *v w* and bolts *a*, substantially as and for the purpose set forth.

30 4. In combination with the lever O, provided with set-screw *b*, the pendulum-rod *p*, suspended on pin *q*, said rod provided near its upper end with a projecting arm, *r*, and at its lower end with side pins, *o*, operating in the

slots *n* of the arms *m*, carrying a pawl, *t*, for moving the ratchet-wheel *l*, substantially as and for the purpose set forth.

5. In combination with the pendulum *p*, 40 provided with arm *r*, the rack *h* and pinion *i*, and the ratchet mechanism whereby the table or trough G is operated, the levers O, with mechanism described for imparting motion to the pendulum at each upward stroke of the 45 said levers, substantially as and for the purpose specified.

6. In combination with the pendulum *p*, having an arm, *r*, the arms *m m'*, rack *h*, and pinion *i*, the pivoted levers O, having set-screw *b* fitted in the lower part of one of the 50 same, as described, and the wheels L', with connecting-levers N, substantially as and for the purpose set forth.

7. The arrangement of shaft K', carrying 55 pulley M and pinions L, the shaft K, carrying gear-wheel L', having pins *u u'*, the shaft R, with its levers O, the beater T, and the connecting angle-braces *y*, and levers P and N, in combination with the rack *h*, pinion *i*, and 60 the pendulum *p*, having arm *r*, said pendulum connected with the levers *m* of a ratchet mechanism, whereby the table or trough G is operated, substantially as described, and for the purpose set forth.

In testimony whereof I affix my signature in presence of two witnesses.

EMILE FERDINAND DEL BONDIO.
